(57) **CLAIM**

The ornamental design for a wind turbine, as shown and described.

DESCRIPTION

FIG. 1 is a front perspective view of the wind turbine of the present invention, with the pole broken away to indicate indeterminate length;

FIG. 2 is a side elevational view of the wind turbine of FIG. 1, with the pole broken away to indicate indeterminate length;

FIG. 3 is a front elevational view of the wind turbine of FIG. 1, with the pole broken away to indicate indeterminate length;

FIG. 4 is a top plan view of the wind turbine of FIG. 1;

FIG. 5 is a bottom plan view of the wind turbine of FIG. 1; and,

FIG. 6 is a rear elevational view of the wind turbine of FIG. 1, with the pole broken away to indicate indeterminate length.
